UNITED STATES PATENT OFFICE.

CHARLES J. FOLLMER, OF NEW YORK, N. Y.

DESIGN FOR A PARASOL.

45,802.

Specification for Design.

Patented May 19, 1914.

Application filed January 20, 1914. Serial No. 813,334. Term of patent 14 years.

To all whom it may concern:

Be it known that I, CHARLES J. FOLLMER, a citizen of the United States, residing at Manhattan, city of New York, in the county of New York and State of New York, have invented a new, original, and ornamental Design for Parasols, of which the following is a specification, reference being had to the accompanying drawing, forming a part thereof.

In the drawings forming a part of this

specification, Figure 1 is an elevation of a parasol showing the design, and Fig. 2 is a plan view thereof.

I claim:—

The ornamental design for a parasol as shown.

CHARLES J. FOLLMER.

Witnesses:

W.M. W. McCONNELL,
EDITH WOOD.
